Primary Examiner — Catherine A Tuttle*(74) Attorney, Agent, or Firm* — Polsinelli PC(57) **CLAIM**

The ornamental design for a dispensing bottle with retractable head, as shown and described.

DESCRIPTION

FIG. 1 is a top perspective view showing my new design for a dispensing bottle with the cap element in a retracted state;

FIG. 2 is a front view thereof;

FIG. 3 is a back view thereof;

FIG. 4 is a left side view thereof;

FIG. 5 is a right side view thereof;

FIG. 6 is a top plan view thereof;

FIG. 7 is a bottom plan view thereof;

FIG. 8 is a top perspective view showing the cap element in a deployed state;

FIG. 9 is a front view thereof;

FIG. 10 is a back view thereof;

FIG. 11 is a left side view thereof;

FIG. 12 is a right side view thereof;

FIG. 13 is a top plan view thereof; and,

FIG. 14 is a bottom plan view thereof.

The broken lines of FIGS. 7 and 14 depict the portion of the bottom surface that forms no part of the claimed design.

1 Claim, 14 Drawing Sheets(56)
